(57) **CLAIM**

The ornamental design for a remote control for a drone, as shown and described.

DESCRIPTION

1.1 is a front view of remote control for a drone, shown with a closed support;

1.2 is a rear view thereof;

1.3 is a left view thereof;

1.4 is a right view thereof;

1.5 is a top plan view thereof;

1.6 is a bottom plan view thereof;

1.7 is a perspective view thereof;

2.1 is a front view of the remote control for a drone, shown with an open support;

2.2 is a rear view thereof;

2.3 is a left view thereof;

2.4 is a right view thereof;

2.5 is a top plan view thereof;

2.6 is a bottom plan view thereof; and

2.7 is a perspective view thereof.

The portions of the remote control for a drone shown in broken lines form no part of the claimed design.
